Primary Examiner — Mark Goodwin(74) *Attorney, Agent, or Firm* — Mark E. Scott; Conley Rose, P.C.(57) **CLAIM**

The ornamental design for the musical system, as shown and described.

DESCRIPTION

FIG. 1 is a front perspective view of a musical system showing our new design;

FIG. 2 is a side elevation view thereof;

FIG. 3 is a side elevation view thereof;

FIG. 4 is a rear elevational view thereof;

FIG. 5 is a front elevation view thereof;

FIG. 6 is a top plan view thereof; and,

FIG. 7 is a bottom plan view thereof.

The components depicted in broken lines are for illustrative purposes only and form no part of the claimed design.
